UNITED STATES PATENT OFFICE.

HARRY S. CORNISH, OF NEW YORK, N. Y., ASSIGNOR OF ONE-THIRD TO HORACE B. CHRISTIAN, OF RICHMOND, VIRGINIA.

LIQUID-DISPENSING APPARATUS.

1,212,186.

Specification of Letters Patent. Patented Jan. 16, 1917.

Application filed August 19, 1909. Serial No. 513,565.

To all whom it may concern:

Be it known that I, HARRY S. CORNISH, a citizen of the United States, and a resident of New York, in the county of New York and State of New York, have invented certain new and useful Improvements in Liquid-Dispensing Apparatus, of which the following is a specification.

My present invention relates to liquid dispensing apparatus, and more particularly to such apparatus as is used in dispensing drinks which are made up of a flavoring syrup and a liquid, such as water under pressure, preferably drawn simultaneously.

The main object of the invention is to provide a liquid dispensing apparatus of this type which will positively deliver a drink such as water and a flavoring syrup of the same constituency under variations of pressure of the liquid used.

A further object is to so construct the apparatus that the constituency of the drinks can be changed to any desired degree and the changed condition will remain the same under variations of pressure.

In liquid dispensing apparatus, when it is desired to dispense flavored drinks such as are made up of carbonated water, or ordinary water under pressure, and a flavoring syrup, either one of two modes of operation is employed. In one, the operator first draws the syrup and then adds the water, leaving entirely within his control the character of the drink; while in the other, the flavoring syrup and water are both drawn simultaneously, in which latter operation, the character of the drink is not within his control. In the latter case the pressure of the charged water, or liquid under pressure, varies from time to time and therefore the drink will contain more or less of this liquid as the case may be and its constituency correspondingly varies. Further if left to the control of the operator to make allowance for the variations in pressure, the different drinks drawn will not be uniform.

By my invention, in its preferred form, I provide a gage in the pipe connection for the pressure water and a regulator which controls the amount of liquid under pressure which flows to the dispensing faucet. This regulator is so constructed that with a certain size opening and the liquid at a given pressure, a definite amount of liquid will be delivered into the drinking

glass, for instance, 8 ozs. in 5 seconds. I also provide a scale which coöperates with an indicator secured to the regulator and which is graduated to pounds pressure to correspond with the indications on the gage and by means of which it is known that, if the indicator on the gage stands at 80 lbs. and the indicator on the regulator is turned to 80 on the scale, the regulator is opened a sufficient amount to deliver 8 ozs. of water in 5 seconds. If the pressure drops to 60 lbs. as shown on the gage, the indicator on the regulator is turned to 60 on the scale, which opens the valve in the regulator wider and 8 ozs. of water is still delivered in 5 seconds. The flow of syrup is delivered into the drinking glass at a uniform rate, which does not vary, according to the size of the passage through which it is delivered so that the amount of syrup delivered is always uniform, which amount is usually 1 oz. in 5 seconds.

In the apparatus which will be herein described, the graduations on the scale are determined by the pressure, the size of the opening through which the liquid flows and the pitch of the screw thread on the valve stem.

If it is desired to vary the constituency of the drink, that is make it more or less sweet, means are provided whereby the scale can be shifted so that if the indicator on the regulator is set at the pressure mark, more or less water will be delivered than before, but nevertheless, each drink drawn at this new proportion will be the same.

My invention consists in a liquid dispensing apparatus to which liquid under pressure and a syrup is delivered and means whereby drinks of uniform constituency will be delivered under variations of pressure of the liquid.

My invention also consists in the combinations of parts and details of construction hereinafter more particularly described and then specified in the claims.

In the accompanying drawings which illustrate my invention as applied to a liquid dispensing apparatus in my preferred form adapted to deliver a flavored drink, Figure 1 is a general diagrammatic view, partly in section, of an apparatus to which my invention is applied. Fig. 2 is a plan view of a part thereof. Fig. 3 is an enlarged central section through the dispens-

ing faucet. Fig. 4 is a similar section, the regulator being shown in a different position. Fig. 5 illustrates diagrammatically the pressure gage and the regulator scale. Fig. 6 is an enlarged view of the regulator scale.

While my invention is herein shown and described as carried into effect in a liquid dispensing apparatus in which a flavored beverage such as a syrup and carbonated or other water under pressure, is delivered, it will be understood that this use is but one part thereof, and it is capable of use for dispensing other mixed drinks without departing from the spirit of my invention.

1 indicates a source of liquid under pressure such as carbonated water or ordinary city water and 2 indicates a container within which is located a coil of pipe 3. The 10 container 2 forms a cooling chamber within which ice may be packed if desired, to surround and cool the various liquid receptacles and conduits located therein. The coil 3 is connected to the source of supply by pipes or conduits 4, the liquid under pressure being delivered to the coil and finally through a pipe 11 to a dispensing faucet 5 located on the outside of the container 2.

20 6 indicates a suitable valve in the pipe 4 for shutting off the supply to the coil 3, and 7 indicates an ordinary pressure gage to indicate the pressure of the liquid fed to the coil 3.

30 The syrup supply is contained in a tank 8 which is always kept filled to the same level from a source 9 on the principle of the inverted bottle. A suitable opening in the bottom of the tank 8 is connected to the faucet 5 by a pipe or conduit 10 through which the syrup is supplied under a constant pressure rendered so by the fact that the tank 8 is always kept filled to the same level, this structure and principle being well understood.

40 The preferred form of dispensing faucet comprises a disk 12 turning on a seat 13 formed in the main body portion 5 of the faucet, said disk being provided with a suitable operating handle 14 secured to the stem 15 to which the disk 12 is secured. The seat 13 is provided with a compressible substance 16 upon which the disk 12 turns.

50 The faucet body 5 is provided with ports or passages communicating with the connecting pipes from the sources of liquid and syrup supply. A port 17 communicates with the pipe 11 for the liquid under pressure and a port or passage 18 communicates with the syrup pipe 10.

60 19 indicates the mixing chamber closed by a cap 20 and is provided with an outlet or spout 21. A port 22 in the valve disk 12 is adapted to register with the port or passage 17 in the valve seat 13 and establish

70 communication between the source of liquid under pressure and the mixing chamber 19. A second port 23 in the valve disk is adapted to register with the port or passage 18 in the valve seat and establish communication between the syrup supply and the mixing chamber. The size of the port 23 determines the amount of flavoring syrup drawn, which is always a fixed quantity and in the present instance 1 oz. in 5 seconds. 75 The ports 22 and 23 are adapted to register with the passages 17 and 18 simultaneously so that the pressure liquid and syrup will be drawn at the same time, suitable stops being provided to limit the movement of the valve disk in one direction when the ports are registered and in the other direction when they are closed, as well-known in the art.

80 To allow for variations in the pressure of the liquid delivered to the faucet from the source 1, regulating means are provided at any suitable part of the apparatus whereby the said means will operate preferably on the pressure liquid supply faucet and present a larger or smaller passage for the flow of liquid. In the present instance the regulator is preferably secured to the dispensing faucet 5 and preferably operates on the pressure liquid passage 17 therein. The 85 passage 17 is provided with a valve seat 24 which is engaged by a suitable shoulder or valve formed on the end of a threaded spindle 25 which passes laterally through the body of the faucet and is provided with a 90 cap 26 on its outer end. The valve spindle 25 is suitably packed to prevent leakage and engages or disengages the valve seat 24, presenting a passage of greater or less size for the flow of liquid to the mixing chamber of 95 the faucet by turning the spindle 25 in one direction or the other.

100 27 indicates a plate preferably secured to the faucet body at or near the cap 26 of the spindle 25. The plate is preferably made 105 semicircular and is provided with a scale graduated to indicate pounds pressure to correspond with the pressure gage 7. An indicator arm 28 secured to the spindle cap 26 moves over the scale on the plate 27 as 110 the spindle 25 is rotated to increase or diminish the size of the opening between the valve seat 24 and the end of the spindle 25, the scale being so arranged that when the indicator 28 stands at, for instance, 60, the 115 opening will be larger than if it stood at 80.

120 In the operation of the device when the pressure of the liquid supplied is 80 lbs. as shown on the pressure gage 7, the indicator 28 is placed at 80 on the scale 27 and the 125 opening in the passage 17 is sufficient to permit say 8 ozs. of water in 5 seconds to pass through. Should the pressure drop to 60 as shown on the gage, the indicator arm is then turned to 60 on the scale, which opens 130

the passage wider and still 8 ozs. of water are delivered in 5 seconds. As a constant stream of syrup is supplied say 1 oz. in 5 seconds, determined by the size of the port 23 in the valve disk or by other means if 5 desired, the constituency of the drinks will always remain the same, no matter what the pressure may be, as the same amount of pressure liquid is delivered per period of time under all pressures.

10 If it is desired to make the drink sweeter, the indicator arm 28 could be kept at say 20 lbs. lower than the pressure indicated on the gage 7, but this would be an unreliable 15 and unsatisfactory way of accomplishing the desired result, as a clerk attending the apparatus would have to remember, if the pressure varied, that he would always have to keep the indicator arm 28 pointed to 20 lbs. lower than the number of pounds indicated on the pressure gage. To avoid leaving the character of the drink to the control 20 of the operator, I mount the plate 27 on its support by a screw or other fastener 29 which passes loosely through a segmental 25 slot 30 in the plate 27 and fastens in the support. Now, when it is desired to make the drink sweeter, the screw 29 is loosened and the plate 27 turned so as to bring a higher 30 number on the scale in the former position of a lower number and the plate fastened. The indicator arm 28 is then always kept at a number corresponding to that indicated on the gage and drinks of the same constituency 35 will always be drawn in the new proportion. To make the drink less sweet, the reverse movement of the plate 27 is made, the amount of advance or lead given the plate determining the proportions of the 40 drink.

The scale on the plate 27 is determined by considering the pressure, the size of the liquid passage in the main valve disk and the pitch of the thread on the valve spindle 25.

45 What I claim as my invention is:

1. In a liquid dispensing apparatus, the combination with a source of water supply, of a dispensing faucet, means for delivering 50 syrup to said faucet at a constant rate, a regulator for the water supply and means for indicating the position of said regulator.

2. In a liquid dispensing apparatus, the combination with a source of water supply, 55 of a dispensing faucet, means for delivering syrup to said faucet, a pressure gage for the water supply, a regulator for the water supply adjustable in accordance with the indication of the pressure gage to dispense a drink of the same constituency under variations of pressure of the water and means for determining the position of the regulator for the variations of pressure.

3. In a liquid dispensing apparatus, the 60 combination with a source of liquid under

pressure, of a dispensing faucet connected thereto, means for delivering a syrup to said faucet at a constant rate, means for simultaneously drawing said liquid and said syrup, a pressure gage for said pressure liquid, 70 a regulator for said pressure liquid and a scale graduated in pounds pressure to correspond with said gage whereby drinks of the same constituency may be drawn under variations of pressure.

4. In a liquid dispensing apparatus, the combination with a source of liquid under pressure, of a dispensing faucet connected thereto, means for delivering a syrup to said faucet at a constant rate, means for simultaneously drawing said liquid and said syrup, 80 a pressure gage for said liquid, a regulator on said faucet adapted to control the flow of pressure liquid, a disk graduated to correspond with said pressure gage and an indicator 85 on said regulator whereby drinks of the same constituency may be drawn under variations of pressure.

5. In a liquid dispensing apparatus, the combination with a source of liquid under 90 pressure, of a dispensing faucet connected thereto, means for delivering a syrup to said faucet at a constant rate, means for simultaneously drawing said liquid and said syrup, a pressure gage for said pressure liquid, a 95 regulator for said pressure liquid, a scale graduated in pounds pressure corresponding with said pressure gage and an indicator for said regulator whereby drinks of the same constituency may be drawn in equal periods 100 of time under variations of pressure or drinks of different constituencies may be drawn in the same periods of time.

6. In a liquid dispensing apparatus, the combination with a source of liquid under 105 pressure, of a dispensing faucet connected thereto, means for delivering a syrup to said faucet at a constant rate, means for simultaneously drawing said liquid and said syrup, a pressure gage for said pressure liquid, a 110 regulator for said liquid, a scale graduated to correspond to said pressure gage and having a definite relation thereto, means connected with said regulator and co-operating with said scale whereby drinks of the same 115 constituency may be drawn under variations of pressure and means for changing the relation of said gage and said scale to vary the constituency of the drinks.

7. In a liquid dispensing apparatus, the 120 combination with a source of water supply, of a dispensing faucet, means for delivering syrup to said faucet, means for indicating the pressure of said water supply, regulating means adapted to be set in accordance with 125 the reading upon said indicating means whereby drinks of uniform constituency may be drawn under variations of pressure of said water and means for determining the position of the regulating means to permit it 130

being adjusted to correspond to the pressure indicating means.

8. In a liquid dispensing apparatus, the combination with a source of liquid under pressure of a dispensing faucet, means for delivering a flavored liquid to said faucet, a gage for the pressure liquid, a regulator for one of said liquids adapted to be set in accordance with the reading upon said gage whereby drinks of uniform constituency may be drawn under variations of pressure of said water and means for determining the position of said regulator to permit it being adjusted to correspond to the pressure indicating means.

9. In a liquid dispensing apparatus, the combination of a source of liquid under pressure, of a dispensing faucet connected thereto, means for delivering a syrup to said faucet at a constant rate, means for simultaneously drawing said liquid and said syrup, a pressure gage for the pressure liquid, a regulator and a rotatable scale graduated to correspond to said pressure gage and having a definite relation thereto, and adapted to be set according to the indications of the pres-

sure gage in such manner that drinks of the same constituency may be drawn under variations of pressure of the pressure liquid.

10. In a liquid dispensing apparatus for delivering mixed drinks, the combination with a source of water supply under pressure, of a dispensing faucet, means for delivering syrup to said faucet at a constant rate, a gage for indicating the pressure of said water supply, a regulator located on the pipe carrying the water and adapted to vary the size of the liquid passage of said pipe and a scale for determining the position of the regulator to permit it being adjusted to correspond to the indications on said gage so as to deliver a mixture of uniform constituency under variations of the pressure of the water.

Signed at New York in the county of New York and State of New York this 10th day of August A. D. 1909.

HARRY S. CORNISH.
